UNITED STATES PATENT OFFICE.

JEAN ALFRED LEU, OF MONTREAL, CANADA, ASSIGNOR OF ONE-HALF
TO NUMA HUGUENIN, OF MONTREAL, CANADA.

BOTTLE SUPPORT AND PROTECTOR.

SPECIFICATION forming part of Letters Patent No. 784,868, dated March 14, 1905.

Application filed June 9, 1904. Serial No. 211,763.

To all whom it may concern:

Be it known that I, JEAN ALFRED LEU, a subject of the King of Great Britain, residing in the city and district of Montreal, in the Province of Quebec, Canada, have invented certain new and useful Improvements in Bottle Supports and Protectors; and I do hereby declare that the following is a full, clear, and exact description of the invention, such as will enable others skilled in the art to which it appertains to make and use the same.

This invention relates to new and useful improvements in bottle-supports and protecting means coöperating therewith whereby a bottle may be supported in position while extracting the cork or stopper and be so protected or inclosed as to guard against injury to the person extracting the cork therefrom.

The object of the invention is to provide a device of the character described which may be connected with a counter or bar and be supported in position in proximity to the cork-extracting device commonly used in bar-rooms, &c., all as hereinafter fully described, and specifically pointed out in the claim.

The annexed drawing represents a fragment of a bar or counter with my device supported in position thereupon with a portion of the device shown in vertical section for convenience of illustration.

Referring to the parts, 1 indicates the counter to which may be connected the cork-extractor 2, provided with the usual operating-handle 3 and corkscrew spiral 4. Connected with the under side of the bar is a supporting-plate 5, which is preferably bifurcated at its outer end, and between the bifurcations of this plate is pivotally supported a rod or standard 6, the pivot 7 therefor extending transversely through the plate 5. The lower end of the rod 6 is provided with an enlargement or offset 8, which serves as a stop to prevent accidental displacement of the bracket 9, having at its inner end the sleeve 10, which is slidable upon the rod 6, while set-screws 11 project through such sleeve and are adapted to bear against the face of the rod 6 to lock

the bracket in any desired position longitudinally of the rod. The outer end of the bracket 9 is perforated, as shown, and projecting through the perforation is a stem 12, which connects with the bracket the plate 13 and to such plate the cup-shaped bottle-receptacle 14. For convenience of operation it is preferred that the plate 13 and receptacle 14 be rotatable upon the bracket 9, and the receptacle 14 is formed of sufficient size to permit inserting therein bottles such as are ordinarily used for containing liquids, &c. For convenience the receptacle 14 is preferably frusto-conical in shape and may be of any suitable material.

Coöperating with the receptacle 14 is a cover or cap 15, which is preferably formed of hard rubber, metal, or any other desirable material which will be light and which may be placed over the upper portion of a bottle, as 16, which may be placed in the receptacle 14. Within the upper portion of the cap 14 is placed a ring or collar 17, which is preferably of metal, and the cap 14 is secured thereto in any desired manner.

In operation the device is secured to the bar and the bottle is placed in the receptacle 14, after which the cap 15 is placed over the upper portion of the bottle and the device is swung into position beneath the cork-extractor 2, whereupon the corkscrew 4 may be projected into the bottle-stopper and said stopper withdrawn. If the bottle should accidentally become broken during the time of withdrawing the stopper, it is evident that the hands of the person manipulating the device will not be injured by reason of the broken glass, as the bottle is entirely covered by the receptacle 14 and cap 15.

Owing to the increased thickness of the collar 17 it is evident that such collar will serve as an abutment between the upper portion of the bottle-neck and the cork-extracting device 2 when upward draft is applied to the bottle-stopper.

While I have shown in the accompanying drawing the preferred form of my invention, it will be understood that I do not limit myself to the precise form shown, for many of the details may be changed in form or posi-

tion without affecting the operativeness or utility of my invention, and I therefore reserve the right to make all such modifications as are included within the scope of the following claim or of mechanical equivalents to the structures set forth.

Having described my invention, what I claim, and desire to secure by Letters Patent, is—

- 10 In a bottle-support for stopper-extractors, a fixed plate, a rod pivoted to said plate to swing in a vertical plane beneath the stopper-extractor; a bracket slidingly and adjust-

ably mounted on said rod, a bottle-holder rotatably mounted on said bracket, the same 15 having a socket in the shape of a frustum of a cone, whereby it is adapted to hold different sizes of bottles, and a cap-shield for the upper part of the bottle adapted to coöperate with said bottle-holder.

In witness whereof I have hereunto set my hand in the presence of two witnesses.

JEAN ALFRED LEU.
